GEORGE B. KELLY, OF JAMAICA PLAIN, MASSACHUSETTS.

COMBINED PLAYER PIANO AND ORGAN.

1,042,686.

Specification of Letters Patent. Patented Oct. 29, 1912.

Application filed October 6, 1911. Serial No. 653,160.

To all whom it may concern:

Be it known that I, GEORGE B. KELLY, a citizen of the United States, and a resident of Jamaica Plain, in the county of Suffolk and State of Massachusetts, have invented certain new and useful Improvements in Combined Player Pianos and Organs, of which the following is a specification.

This invention relates to a combined player piano and organ.

The object of my invention is to combine a player piano and organ in such a manner that the player piano can be played manually or by means of a record sheet in the conventional manner independently of the organ, or the organ can be played by means of a record sheet independently of the piano, or the organ and piano can be played at the same time by means of one record sheet and either one of two subdivisions of the organ or both can be played by means of a record sheet with or without controlling the piano player mechanism, automatically by means of the same record sheet, all of which is simple in construction, compact and reliable and effective, in use and in action.

In the accompanying drawings in which like letters of reference indicate like parts in all the figures: Figure 1 is a vertical transverse sectional view representing diagrammatically one embodiment of my improved combined player piano and organ. Fig. 2 is a detail face view of part of the tracker. Figs. 3 and 4 are detail views of the coupling mechanism.

The combined instruments are contained in a casing represented by 1 and within this casing the player piano 2 is contained, which has the usual frame, sounding-board, strings, hammers, etc., all of conventional construction. A series of pneumatics 3, of conventional construction, are provided for operating the piano action pneumatically, which action can also be operated manually in the conventional manner by means of keys 4. The pneumatics 3 are connected with a wind-chest 5 from which air is exhausted through the bellows 6 by means of the pumping bellows 7 operated by the foot treadles, all in the conventional manner of a player piano, and the piano player mechanism is thus operated by rarefied air in the usual manner. Each striker pneumatic 3 is controlled by a valve 9 which in turn is operated by a pouch over a recess 10 connected with a duct 11 in any conventional manner.

The wind-chest and the striker pneumatics are preferably arranged above the keys, and a music box 12 is also located above the keys, the front of which music box can be closed 60 by a tight fitting sliding glass door 13 at or near the front of the casing 1. Within the music box the conventional music and take-up rolls are mounted and are shown by dotted lines in the drawings and between them is 65 located a tracker bar 14 which has three rows of tracker ducts marked respectively 15, 16 and 17. Preferably the two upper rows 16 and 17, each contain fifty-eight ducts, as this number is usually provided in pneumatic playing organs making use of a record sheet and these ducts are staggered as shown in Fig. 2. The lower row 15 which is to be used for the piano only has eighty-eight ducts, that is, one for each hammer as 70 75 is now generally practised in piano players.

Each duct of the lower row 15 is connected by a tube 18 with a fixed rail 19 having a row of ducts passing vertically through it so that eighty-eight openings appear on 80 the underside of this rail 19 in a straight row. A sliding rail 20, resting flat against the underside of the rail 19 so as to form an air tight joint and to slide transversely to the rail 19, can be shifted by means of a 85 suitable rod or other appliances 21 extending to the front of the music box and which may be of any approved construction, and in the drawings here shown, is a straight rod with a handle at the outer end. This 90 lower rail 20 is provided in its upper surface with the ends of eighty-eight ducts which can register with the lower ends of the eighty-eight ducts terminating in the under surface of the fixed rail 19 and the 95 said eighty-eight ducts in the rail 20 are each connected by a flexible tube 22 with one of the ducts 11 leading to a recess 10 beneath the pouch for operating the valve 9 of a pneumatic striker mechanism. Forty- 100 five ducts are formed in the fixed rail 19 in the row behind the eighty-eight ducts and also terminate in the underside of the fixed rail and are spaced precisely the same as the ducts in the eighty-eight row so that when 105 the movable rail 20 is brought into position shown in Fig. 3 forty-five of the ducts in the movable rail 20 will register with forty-five corresponding ducts in the rear row of ducts in the fixed rail 19 and these forty-five ducts 110 in the rear row of the fixed rail are each connected by a tube 23 with a valve mecha-

nism of the organ, as will be described later on.

The organ is operated by pressure wind in the conventional manner, which wind is generated by a motor operated pumping bellows 24 delivering the compressed air into the chambers 25 and 26 connected by a duct 8, the chamber 26 communicating with an equalizing bellows 27, the movable board of which is connected with a spring 28 which normally tends to keep the equalizing bellows collapsed. The air under pressure is delivered from the chamber 27 through the pipe 29 to the various parts of the organ.

15 The organ in the present case is divided into two sections, namely the great organ and the swell organ, each having a certain number of reeds which are divided into a certain number of stops, all of which are 20 constructed and manipulated in the conventional way in playing the great organ or swell organ.

In the drawings 30 represents a tone producer of the great organ and 31 a tone 25 producer of the swell organ, and it is to be understood that these are divided into two sections as stated and then again into groups controlled by stops in the conventional manner.

30 As the tone producers are practically all the same I will describe only one. The reed 32 is contained in a reed chamber 34. Each reed chamber is normally closed by a spring-pressed valve 35 opening into the chamber 36 into which air under pressure is conducted through the opening 37 from the tube 29, this opening 37 being controlled by means of an ordinary stop. Of course, the chamber 36 applies to a greater or less number of reeds of different pitch. The valve 35 is connected by a rod 38 with a pouch 39 over a recess 40 which is connected by a duct 41 with a valve chamber 42 containing a double valve 43 on a pouch 44 over a recess 45 communicating with a compressed air conduit 46. The double valve 43 serves for connecting the duct 41 with atmospheric air or with a chamber 47 containing air under pressure. As shown, the ducts 41 are 50 each in communication with a chamber 46 containing air under pressure and this air acting on the diaphragm 39 serves to hold the valves 35 closed, these valves being held upon their seats by their springs.

55 When the valve 43, of which there is one for each reed, is raised, the corresponding duct 41 is connected with atmospheric air and the air pressure existing in the chamber 36 presses the corresponding pouch 39 into its recess 40 and as the area of the pouch is greater than that of the corresponding valve 35 with which it is connected the valve 35 is opened, notwithstanding that it is also subjected to the pressure of air 60 in the chamber 36 and as long as this valve

35 remains open the corresponding reed 32 is sounded. With the duct-board 48 a series of longitudinal chambers are connected and these chambers are marked 49, 50, 51, 52 and 53, respectively. The chamber 49 is connected by a U-shaped channel 54 with a recess 55 over which there is a pouch 56 carrying the stem of a valve 57 which controls one of the tubes 23 leading to the fixed rail 19, previously mentioned, and when this valve is raised it admits atmospheric air into the tube 23 and when the sliding rail 20 is adjusted as shown in Fig. 3 this atmospheric air can pass into the duct 22 and cause the operation of the corresponding valve 9 of the piano player. A duct 58 also terminates in the chamber 49 and these two ducts are covered by a pouch 59 in the chamber 49 and are both closed when air, under pressure, is admitted into this chamber 49, which admission of air into this chamber is controlled by the stop 60 which is diagrammatically represented in Fig. 1. The lower end of the duct 58 is in communication with the chamber 50 and with the same chamber 50 U-shaped duct 61 is connected both of which ducts can be closed by a pouch 62 in the chamber 50, when compressed air is admitted into this chamber, which admission of air is controlled by the stop 63 diagrammatically represented in Fig. 1. The U-shaped duct 61 is connected by a tube 64 and a duct 65 leading to the recess 45 pertaining to the double valve for the corresponding note in the swell organ 31. This duct 65 has its lower end connected with the chamber 53 and from this chamber 53 the tube 66 leads to another mechanism to be described later and the lower ends of the duct 65 and the duct 66 can be closed by a pouch 67 in the chamber 53 which chamber is also provided with a stop shown diagrammatically. A branch duct 68 leads from the duct 66 to the chamber 52 and a duct 69 terminating in the chamber 52 is connected with the tube 46 which in turn is connected with the recess 45 beneath the pouch of the double valve 43 pertaining to the great organ 30. The ends of the ducts 68 and 69 in the chamber 52 can be closed by the pouch 70 contained in the chamber 52 which chamber is controlled by a stop shown diagrammatically in the drawing. A branch duct 71 leads from the duct 70 into the chamber 51 and from the same chamber a duct 72 leads to a mechanism to be described later, and the ends of these two ducts 71 and 72 in the chamber 51 can be closed by a pouch 73, this chamber being also provided with a stop shown diagrammatically. A duct 74 connects the duct 72 with the duct 58, previously mentioned.

The forty-five ducts of the upper row 17 in the tracker board are each connected by a tube 75 with a recess over the pouch 76 130

carrying a double valve 77 controlling the tube or duct 66 leading into the chamber 63. When this valve 77 is raised the tube or duct 66 is connected with a chamber 78 into which compressed air is conducted from the compressed air reservoir, through the tube 79. In a similar manner each duct in the row 16 in the tracker board is connected by a tube 80 with a recess beneath the pouch 81 supporting the stem of a double valve 82 which controls the duct or passage 72 leading to the chamber 51 and when this valve is raised compressed air is conducted from the chamber 83 into the tube or duct 72, compressed air being conducted into the said chamber 83 through the tube 84 which is also connected with the compressed air supply. Compressed air is admitted into the music box 12 through the port 85 which can be open or closed by means of a valve which in turn can be manipulated by means of a handle 86 at the front of the music box. 87 is a check valve in the tube 72.

The operation is substantially as follows: Assuming that the performer wishes to play the piano only, by means of a perforated music sheet such as are commonly known as eighty-eight note sheet music, the port 85 which admits compressed air into the music box is closed and the sliding plate 13 in the front of the music box is moved to one side so as to admit atmospheric air into the music box and into the ducts of the eighty-eight duct row 15, and the piano player is then operated in the usual manner, it being of course understood that the sliding rail 20 is in the position shown in Fig. 4, so that the tubes 18 are in communication with the corresponding tubes 22 leading to the controlling valves for the striker pneumatics 3.

If now it is desired to play the organ without the piano by means of a correspondingly perforated record sheet, such a record sheet is placed into the music box, the front of the music box is closed, and the port 85 is opened, so as to admit compressed air into the music box, and the sliding rail 20 is brought into position shown in Fig. 3 where- 50 by the lower ends of the tubes 18 leading from the eighty-eight note tracker ducts are closed. Compressed air is admitted into the chamber 49 so as to seat the pouch 59 thereby closing the ducts 54 and 58 and keeping the valve 57 seated so that all operation of the piano mechanism from the organ is prevented. The pumping bellows of the piano player are operated by the feet in the conventional manner for the purpose of shifting the music sheet by means of the well known motor means of the piano player which need not be described as they form no part of the present invention, the pumping bellows of the organ having been started 60 previously.

If now a hole in the record sheet registers with a duct in the lower row 16 compressed air passes through the tube 80 raises the valve 82 and compressed air passes through the duct 72, through the connecting duct 74, the duct 58, into the duct 61, the chamber 50 having been previously opened to the atmosphere. From the duct 61 the compressed air passes through the duct 64 and duct 65 beneath the pouch of the double valve 43 pertaining to the swell organ, whereby said valve is raised and the valve 35 of the corresponding note in the swell organ is opened. When a note hole in the record sheet registers with a duct in the uppermost row 17 compressed air passes through the corresponding tube 75 raises the double valve 77 permitting compressed air to pass through the tube 66 into the branch duct 68, the pouch 67 closing the ducts 65 leading to the chamber 53 as compressed air is now contained in this chamber. At the same time atmospheric air has been admitted into the chamber 52 and compressed air from the tube 66 passes through the duct 90 68 to the duct 69 and from the latter through the tube 46 into the recess 45 pertaining to the double valve 43 of the great organ 30 and thereby atmospheric air is admitted through the corresponding duct 41 to the 95 recess behind the pouch 39 of the valve 35 for the note in the great organ corresponding to the slot in the note sheet registering with said duct in the uppermost row 17 and so on.

If desired, conditions can be reversed and the notes represented by the ducts in the row 16 can be played upon the great organ, and the notes represented by the ducts in the row 17 on the swell organ, as follows: When a slot in the record sheet corresponding to the lower row 16 of ducts in the tracker board registers with one of these ducts compressed air is again conducted through the tube 72. Compressed air is admitted into the chamber 50 to seat the pouch 62 and atmospheric air has been previously admitted into the chamber 51 so that the pouch 73 can be unseated by compressed air passing through the tube 72. Compressed air is also admitted into the chamber 52 to seat the pouch 70 so that the compressed air from the tube 72 can pass through the angle duct 71 and the duct 69, and from the latter to the tube 46 for operating the corresponding 110 valves 43 and 35 of the great organ 50. When an aperture in the record sheet registers with a duct in the uppermost row 17 the valve 77 is seated and compressed air is admitted into the tube 66. Previously compressed air has been admitted into the chamber 52 to seat the pouch 70 and likewise compressed air is admitted into the chamber 50 to seat the pouch 62 and atmospheric air is admitted into the chamber 53 to unseat the 120 125 130

pouch 67 so that compressed air from the tube 66 can pass into the duct 65 and operate the corresponding valves 43 and 35 of the swell organ.

5 When it is desired to play the piano accompaniment with the organ, atmospheric air is admitted into the chambers 49 and 50 so that the corresponding diaphragm 59 and 62 are unseated. If now air is admitted 10 from the music box by the lifting of the valve 82, into the tube 72 the air will pass into the duct 74 the lower end of the duct 72 having been closed by the pouch 73 by compressed air being previously admitted 15 into the chamber 51. Compressed air passes from the duct 74 into the duct 54 and lifts the valve 57 corresponding to the note to be played and atmosphere will pass through the tube 23, the registering ducts in the rails 20 19 and 20, and the tube 22 to the corresponding player pneumatic. At the same time the valves 43 and 35 of the swell organ are operated and in a like manner numerous combinations can be made.

25 Having described my invention what I claim as new and desire to secure by Letters Patent is:—

The combination with a casing, of an organ therein, constructed to be operated by

air under pressure greater than atmospheric 30 pressure, pneumatic means for playing the organ including air inlet valves, a pneumatic player piano in said casing constructed to be operated by air of less tension than atmospheric air, a tracker board having three 35 rows of tracker ducts, tube connections from one row of tracker ducts to the piano playing mechanism, a movable member for establishing and interrupting the tube connection between said row of tracker ducts and the 40 player piano mechanism, tube connections extending from said movable member to air inlet valves of the organ mechanism, which said tube connections may be brought in communication with the tube connections 45 extending from the said movable member to the pneumatics of the piano player, and means controlled from a row of ducts in the tracker board for operating the previously mentioned air inlet valve of the organ mechanism. 50

Signed at New York city, in the county of New York and State of New York, this 11th day of October A. D. 1911.

GEORGE B. KELLY.
